I. P. Tice

United States Patent Office.

ISAAC P. TICE, OF NEW YORK, N. Y.

Letters Patent No. 67,083, dated July 23, 1867.

TOY BALL-PLAYER.

The Schedule referred to in these Letters Patent and making part of the same.

TO ALL WHOM IT MAY CONCERN:

Be it known that I, ISAAC P. TICE, of the city, county, and State of New York, have invented a new and improved Toy Ball-Player; and I do hereby declare that the following is a full, clear, and exact description of the same, reference being had to the accompanying drawings, making a portion of this specification, in which—

Figure 1 is a perspective view of a toy ball-player constructed according to my invention.

Figure 2 is a vertical longitudinal section of the same.

Similar letters of reference indicate corresponding parts in both figures.

The object of this invention is to obtain a toy in which the movement of the players in base-ball, croquet, and other similar games in which a ball is used, will be closely imitated. The invention consists in a novel combination of parts, whereby a vibrating or impelling movement is communicated to the arm or arms of one or more figures representing the players, so as to propel the ball in a manner imitating that in which it is struck in the practice of the game. The invention further consists in the combination with one or more of the aforesaid figures of a ball mounted upon a vibrating rod, in such manner that the movements thereof during the working or operation of the apparatus is made to closely resemble the flight or movement of the ball in playing. The invention further consists in three figures representing players, and constructed with vibrating or impelling arms, in combination with the aforesaid ball mounted upon a vibrating rod, whereby the several movements of the players and of the ball in base-ball or equivalent games are very closely copied.

To enable others to understand the construction and operation of my invention, I will proceed to describe it with reference to the drawings.

The box or case which contains the principal portion of the mechanism by which the moving parts of the apparatus are operated is shown at A, and secured upon the top of this box are three hollow figures, marked respectively B, C, and D, which are intended to represent human figures, and which may be made of zinc or other suitable metal, and formed preferably by casting in a so-called "slush-mould." Each of the aforesaid figures is furnished with a pivoted arm, *a*, which is pivoted to the shoulder *b* thereof by means of a small shaft, shown in dotted lines at *a'* in fig. 2, and which extends transversely through the upper portion of the figure. Attached to this shaft *a'*, in the interior of the figure, is a short lever, *c*, to the end of which is attached a rod, *d*, which extends downward through one of the legs *e* of the figure, and has its lower end pivoted to the free extremity of a spring-rod, *f*, in order to insure a sufficient degree of elasticity in the said spring-rod, and is firmly attached to one end of the box A, as indicated at *g'*. Each of these spring-rods *f* is furnished with an inclined projection, *h'*, which projects from one side or edge thereof in the direction of the transverse shaft *g*. The shaft *g* has secured upon it three cams, one of which, a double-throw cam, shown in black outline and marked *k* in fig. 2, acts upon the projection *h'* of that spring-rod *f* which is connected with the figure D. The two other of these cams are single-throw cams, and one of them, shown in dotted blue lines at *k'*, acts upon the projection *h'* of the spring-rod connected with the figure C, while the remaining one, *h''*, shown in red color, acts upon that of the spring-rod connected with the remaining figure B. This shaft *g* is intended to be rotated, in the direction of the arrow shown in fig. 2, by means of a crank in in or when it is desired to automatically operate the apparatus through the agency of suitable clock-work. A vibrating rod, *n*, has its lower end pivoted within the box A, as indicated at *o*, and extending upward through a longitudinal slot in the top of the box A, has secured upon its upper extremity a ball, *E*, in such manner that the rod *n* being vibrated or thrown to and fro upon its pivot *o*, the said ball will be caused to strike alternately against the hands or lower portions of the arms *a* of the figures B D, except when interrupted by the arm *a* of the figure C, as will presently be fully set forth. The arm *a* of the said figure C is furnished with a spur or extension, *a**, which is designed to be shaped in imitation of a base-ball or other similar club or bat, and the aforesaid figure C is so situated, at the rearmost edge of the top of the box A, that when the arm *a* thereof is extended or moved outward therefrom, the projection *a** will strike the ball *E* when the rod *n* is in a nearly or quite upright position, or in other words at or about the middle of the flight or movement of the said ball. The several parts being in the position shown in fig. 2, the rotation of the shaft *g* causes the throw *g* of the double-throw cam *k* to leave the projection *h'* of the spring-rod connected with the figure D, whereupon the elasticity of the said rod forces it downward, which draws down the rod *d*, and depressing the lever *c* forces forward or outward the arm *a* of the aforesaid figure D,

thus giving a sudden impulse to the ball E. sufficient to tilt the vibrating rod n upon its pivot o, and throw the ball away from the figure D, whereupon it strikes the lower end of the arm a of the opposite figure B, as hereinbefore mentioned. In the mean time the cam k' raises the spring-bar f of the figure B, thus bringing back the arm o thereof, and as soon as the ball strikes the said arm, as just set forth, the cam k' releases the spring-bar connected therewith, so that the downward movement thereof, operating through the agency of the connecting-rod d and lever e, throws the aforesaid arm suddenly forward and propels the ball back to the arm a of the figure D, which being done, the throw 4 of the cam k, having raised the spring-rod connected with the said figure, suddenly releases the same and operates the arm a of the figure to throw the ball therefrom, but inasmuch as simultaneously with this the cam k'' depresses the spring-rod connected with the arm a of the figure C, and consequently throws outward or extends the said arm, or rather the extension a* thereof, into the path or arc described by the ball in passing from one to the other of the figures B D, as just explained, it follows that the ball striking the said extension a* in its flight, recoils and is thrown back to the arm of figure D. The release of the spring-rod f, connected with the figure C, then enables the elasticity of the said spring-bar to push upward the rod d, and bring back the arm of the aforesaid figure, whereupon the throw 3 of the cam k again operates the arm of the figure D, as hereinbefore fully explained. The ball E is thus thrown to and fro between the figures B and D, but stopped and thrown back to the figure D by the arm of the figure C, at each alternate vibration, thus closely imitating the principal feature of the game of base-ball. If desired the arms of the several figures may be so formed and arranged that the strokes given thereby correspond to those required in croquet or other similar games.

What I claim as my invention, and desire to secure by Letters Patent, is—

1. The combination with one or more figures, substantially such as herein described, of the ball E mounted upon the vibrating rod n, substantially as and for the purpose herein set forth.
2. The three figures B C D, constructed with vibrating or impelling arms a, and arranged in relation with each other, and with the ball E mounted upon the vibrating rod n, substantially as and for the purpose herein set forth.

I. P. TICE.
